US0D1090364S

(12) **United States Design Patent** (10) Patent No.: **US D1,090,364 S**
(45) Date of Patent: ** Aug. 26, 2025

(54) **PART OF A BABY CARRIAGE**

(71) Applicant: **Cybex GmbH**, Bayreuth (DE)

(72) Inventors: **Ralf Holleis**, Bayreuth (DE); **Gabriel Altenhofen**, Bayreuth (DE); **Yuyi Chen**, Bayreuth (DE); **Melanie Indaco**, Bayreuth (DE); **Meike Becker**, Bayreuth (DE)

(73) Assignee: **Cybex GmbH**, Bayreuth (DE)

(**) Term: **15 Years**

(21) Appl. No.: **35/518,402**

(22) Filed: **Mar. 17, 2023**

(80) **Hague Agreement Data**

Int. Filing Date: **Mar. 17, 2023**

Int. Reg. No.: **DM/229866**

Int. Reg. Date: **Mar. 17, 2023**

Int. Reg. Pub. Date: **Sep. 22, 2023**
